(57) **CLAIM**

The ornamental design for an insert for toolboxes, as shown and described.

DESCRIPTION

1., 3. Insert for toolboxes

FIG. 1.1 is a bottom view of an insert for toolbox showing the new design;

FIG. 1.2 is a front elevation thereof;

FIG. 1.3 is a top plan thereof;

FIG. 1.4 is a right side elevation thereof;

FIG. 1.5 is a rear elevation thereof;

FIG. 1.6 is a left side elevation thereof;

FIG. 1.7 is a front, top, and right side perspective view thereof;

FIG. 1.8 is a front, bottom, and left side perspective view thereof;

FIG. 3.1 is a bottom view of a second embodiment showing the new design;

FIG. 3.2 is a front elevation thereof;

FIG. 3.3 is a top plan thereof;

FIG. 3.4 is a right side elevation thereof;

FIG. 3.5 is a rear elevation thereof;

FIG. 3.6 is a left side elevation thereof;

FIG. 3.7 is a front, top, and right side perspective view thereof; and

FIG. 3.8 is a front, bottom, and left side perspective view thereof.

The broken lines illustrate portions of the insert for toolbox and form no part of the claimed design.
